UNITED STATES PATENT OFFICE.

HUGH S. MCKEAN, OF ALLEGHENY, PENNSYLVANIA, ASSIGNOR TO EDWARD S. WRIGHT, TRUSTEE, OF SAME PLACE.

SELVAGE-SHEDDING DEVICE FOR HAND-LOOMS.

SPECIFICATION forming part of Letters Patent No. 400,583, dated April 2, 1889.

Application filed October 25, 1888. Serial No. 289,095. (No model.)

To all whom it may concern:

Be it known that I, HUGH S. MCKEAN, a resident of Allegheny, in the county of Allegheny and State of Pennsylvania, have invented a new and useful Improvement in Selvage-Shedding Devices for Hand-Looms; and I do hereby declare the following to be a full, clear, and exact description thereof.

My invention relates to looms, and more especially to an apparatus for hand-loom, by which an even, regular, and well-compacted selvage will be formed on the material woven.

In the ordinary hand-loom employed in plain weaving the loom-harness consists of two heddles, said heddles being constructed of an upper and lower lath connected by cords parallel with each other and at regular intervals apart. In these cords, midway between the laths, are eyes or loops through which the warp-threads coming from the warp-beam pass, the eyes of one set of cords receiving every alternate warp-thread and the eyes of the other set the remainder. Suitable treadles are employed for raising and lowering said heddles and the corresponding warp-threads, so that when one heddle is raised a shed or opening is formed between the warp-threads of the upper heddle and the warp-threads of the lower heddle, through which 30 shed the shuttle carrying the weft-thread is passed, while the reed is then brought forward to compact the weft and the heddles reversed, so that the warp-threads formerly above will be lowered, and vice versa, when 35 the shuttle is returned, and this operation continued till the desired length of cloth is woven. In this manner the weft-thread is caused to pass alternately above and below the threads of each of the two sets composing 40 the warp until the work is completed.

It is very important in all classes of weaving that the material woven have a selvage even and regular and one which will not ravel. This is easily obtained where looms are employed in which the loom-harness is composed of two or any even number of heddles, for as the shuttle passes from one side to the other the weft-thread twists alternately around the outside warp-thread of the several sets of 50 warp-threads as the heddles are raised and

lowered accordingly. The result will be a selvage closely woven and regular and uniform in appearance; but in weaving with three heddles or any odd number much time and labor are required to produce a material with the same kind of a selvage as where an even number of heddles is employed. Although the result of the first two passes of the shuttle will be the same as in plain weaving with two heddles, yet on the third pass the 55 outside warp-threads would not be caught by the shuttle, and it is necessary to pass the shuttle around this outside thread and so tie it down; and to accomplish this the operator has to stop to pick out the proper warp-thread of the third heddle, in order to pass the shuttle around it to form the selvage. Unless this is done every third pass the weft will form a loop which will project out beyond the regular line of the selvage, detracting from the 60 strength and as well from the appearance of the material woven.

The object of my invention, therefore, is to provide a means of operating hand-loom with an odd number of heddles, so that a compact, 65 regular, and even selvage will be formed on the material woven without the delay and labor occasioned by the operator having to stop to pick out the proper warp around which the weft is wound.

To these ends my invention consists, generally stated, in two cords or wires mounted on each side of the loom, said cords or wires having eyes thereon through which the two separate outside selvage-threads pass, a handle 75 on the lathe of the loom and connections therefrom for raising and lowering said wires and the selvage-threads passing through them.

To enable others skilled in the art to make and use my invention, I will describe the same 80 more fully, referring to the accompanying drawings, in which—

Figure 1 is a side elevation of a loom with my improvement attached, and Fig. 2 is a vertical cross-section looking from the rear of the 85 loom.

Like letters of reference indicate like parts in each of the figures of the drawings.

The ordinary hand-loom, *a*, usually constructed of wood, has at the rear thereof the 90

warp-beam *b*, fitted in suitable bearings and adapted to turn thereon, while around said warp-beam are wound the warp-threads *c*, passing from said beam up over the dead-beam *d*.

Suspended from the top beams, *a'*, of the loom is the loom-harness, consisting of the three heddles *e f g*, said heddles being composed of the laths *e' f' g'*, respectively, arranged parallel to each other, and joining the upper and lower laths are the vertical cords *e² f² g²*, arranged at regular intervals from each other, and having at or near their center the eyes or loops *e³ f³ g³*. These cords differ in number, according to the width of the matting or other material to be woven. The heddles *e f g* are suspended from the beams *a'*, the heddle *g* being suspended by means of the belt *h*, secured to the upper lath of said 20 heddle and passing up over any suitable pulley, *a²*, on the beam *a'*, and down under the upper one of the pulleys *h'* and thence up to the beam *a'*, to which it is secured. The heddles *e* and *f*, joined by any suitable belt or 25 cord, are suspended from the lower one of the pulleys *h'*, while belts or cords *h²* connect the lower laths of said heddles to the arms *i* of the foot-treadles *i'*, so that the heddles may be raised or lowered, as desired. The warp-threads *c*, coming from the warp-beam *b* and 30 over the dead-beam *d*, pass through the loops *e³ f³ g³* alternately, each heddle having its own set of warp-threads, and then through the vertical spaces in the reed *j*, beyond which the matting is formed and wound around the cloth-beam *k*. The lathe *j'* is of ordinary construction, and is suitably balanced on the beam *a'*, so that it may be drawn forward and 35 shoved back by the hand of the operator to 40 drive the weft into place.

In suitable bearings in the beam *a'*, at the top, of the loom and adapted to turn thereon, is a horizontal shaft, *l*, and rigidly secured to said shaft are the pulleys *l'*, while below said 45 shaft *l* in the lower part of the loom is a corresponding horizontal shaft, *m*, turning in suitable bearings in the frame-work of the loom, to which the pulleys *m'* are rigidly secured, said pulleys being in line with the pulleys *l'* above. Around the pulleys *l' m'* pass the 50 belts *n³*, connected by means of wires or cords *n*, said wires being stretched taut between the pulleys, so that the belts cannot slip therefrom, while at about the middle of said wires 55 are formed the eyes or loops *n'*, which are in one plane with the eyes *e³ f³ g³*. And through said eyes *n'*, on each side of the several sets of warp-threads passing through the heddles *e f g*, but independent of said heddles, pass 60 the selvage-threads *n²*—that is to say, these two selvage-threads are operated not by the heddles, but by the wires *n*, passing over the pulleys *l'* and *m'*, so as to form the ordinary loop of the two-thread weaving on the edges 65 of the material woven on a loom in which three heddles are employed.

Attached to the lathe *j'*, near its pivotal

point, are the hangers *o*, the lathe *j'* being so balanced on the beams *a'* that very little, if any, movement will be given to the hangers *o* when said lathe is drawn forward or shoved back. Mounted on these hangers *o* and journaled in suitable bearings thereon are the pulleys *o'*, while directly in front of said pulleys, on the shaft *l*, are mounted the pulleys *p*, 75 rigidly secured to said shaft *l*, and around said pulleys *p* pass the belts or cords *p'*, being securely attached thereto, and then up over the pulleys *o'* and down to the guide-pulleys *o²*, suitably attached to the sword *j²* of the lathe *j'*, 80 and thence to the slide-rod *r*, sliding in a suitable guideway, *r'*, in the upper part, *r²*, of the lathe, to which rod *r* the said belts *p'* are attached, as at *r³*. A suitable handle or thumb-piece, *r⁴*, on the slide-rod *r* furnishes means 85 for sliding said rod to and fro by the hand of the operator.

In describing the operation of a loom with my invention applied thereto I will do so with reference to a loom employed in the weaving 90 of cocoa matting, to which my invention is especially applicable. The several sets of warp-threads passing through their respective eyes on the heddles *e f g* and the selvage-threads passing through the loops *n'* are 95 arranged in the manner hereinbefore described, the said heddles being in alignment with each other and at the same height. The operator from his seat in the front of the loom first raises the heddle *e* by applying his foot to the proper treadle, and by the same movement the warp-threads passing through the eyes *e³* are also raised, while said operator with his hand upon the upper part, *r²*, of the lathe *j'* moves, by means of the handle *r⁴*, the slide-rod *r*, moving easily in the guideway *r'*, which operation acts to draw the belt *p'*, attached to said slide-rod *r*, in the same direction as said slide-rod, and as said belt passes up over the pulley *o²* and around the fast pulley *p* a slight 110 turn will be given to the shaft *l* and also to the shaft *m* through the wires *n*, joining the same. By this movement one pair of the outer selvage-threads, *n²*, passing through to the loops *n'*, will be raised to the height of 115 the warp-threads already raised, passing through the eyes *e³*. In this manner between the upper set of warp-threads and the lower is formed a shed or opening, through which the shuttle carrying the weft is passed from 120 right to left by one hand of the operator, while with the other hand the operator grasps the upper part, *r²*, of the lathe *j'*, and draws the said lathe forward to drive the weft compactly into the body of the cloth, said weft 125 by this operation passing around and under the selvage-thread, passing through the loop *n'*, and also under the set of warp-threads now raised. In pushing back the lathe *j'* to its former position, by simply sliding his hand at the same time in the proper direction it 130 will come in contact with the handle *r⁴*, and, in the manner hereinbefore described, will operate to reverse the position of the selvage-

threads n^2 passing through the loops n' . The set before raised are now lowered, and vice versa, while the heddle e is now lowered and the heddle f raised, whereby another shed is formed of the upper warp-threads passing through eyes f^3 and the lower ones passing through the eyes e^3 g^3 . The operator now, with the shuttle in the left hand, passes it from left to right and with the other hand 10 draws the lathe forward. Again the warp-threads n^2 are reversed in pushing back the lathe, as described, and the heddle f is now lowered and the heddle g raised, which forms a shed, as before, and this operation is continued until the desired quantity of matting 15 is woven.

In weaving, as above described, one of the heddles and its respective warp-threads are always raised so that the upper side of the 20 matting will have the twill thereon, and the operator can tell whether the matting is being perfectly woven and will be able to see any break in the warp-threads.

In operating the selvage-threads n^2 no time 25 is lost, as the operator in pushing back the lathe has only to slide the handle r^4 in either direction, according to the set of threads to be raised, and as said lathe must be pushed back under any circumstances no extra time 30 and labor are expended.

By my invention I am enabled to produce 35 cocoa matting with an even, regular, and compact selvage, for as the selvage-threads n^2 have a movement independent of the other warp-threads passing through the eyes of the several heddles, and as they are raised and lowered alternately the result on the selvage of the matting will be the same as where two 40 heddles are employed, while the body of the matting will have the twill and thickness of texture due to the use of three heddles.

As stated, my invention is especially applicable to hand-loom, being simple in construction and not liable to get out of order, while 45 it supplies a means of weaving matting where

an odd number of heddles is employed, so that the selvage formed will be even and regular without the loss of time and labor necessary when the operator has to stop and wind the weft around the outside warp in order to 50 get a uniform selvage, as in the old form of hand-loom. By my invention no extra time and labor are expended in operating the loom, for as the lathe is shoved back the warps forming the selvage are reversed each time by the 55 same movement, and there is nothing to break the continuity of the operation. As the operation of hand-loom is necessarily slow and attended with delay, anything that will accelerate the working of the same is greatly 60 needed.

What I claim as my invention, and desire to secure by Letters Patent, is—

1. The combination, with the lathe, of two wires or cords at each side of the loom for 65 carrying the selvage-threads, a hand-actuated device on the lathe, and connections therefrom to the selvage-thread wires or cords for operating said wires or cords, substantially as and for the purposes set forth.

2. In a hand-loom, the combination, with the lathe, of two wires or cords carrying the selvage-threads on each side of the loom, a slide mounted on the upper part of the lathe, and connections from said slide to said wires carrying the selvage-threads, substantially as and 75 for the purposes set forth.

3. In a hand-loom, the combination, with the lathe j' , of the wires or cords n for carrying the selvage-threads, the shafts l m , on which 80 they are mounted, the pulleys o' on the lathe, the slide-rod r , and the cords extending from said slide over said pulleys o' to shaft l , substantially as and for the purposes set forth.

In testimony whereof I, the said HUGH S. 85 MCKEAN, have hereunto set my hand.

HUGH S. MCKEAN.
